UNITED STATES PATENT OFFICE.

EDWIN L. STORER, OF TULSA, OKLAHOMA.

SIGNAL.

1,299,057.

Specification of Letters Patent. Patented Apr. 1, 1919.

Application filed August 10, 1917. Serial No. 185,542.

To all whom it may concern:

Be it known that I, EDWIN L. STORER, a citizen of the United States, residing at Tulsa, in the county of Tulsa and State of Oklahoma, have invented new and useful Improvements in Signals, of which the following is a specification.

My invention relates to signals and particularly to that class of signals which are used to indicate the contemplated direction of a motor-car, means being provided whereby the operator thereof may set the signals in any desired position.

A primary object of my invention is to provide a signal of this class which may be easily and quickly operated and which consumes a minimum amount of energy.

A further object of my invention is to provide an electric signal which is simple in construction and efficient in operation.

With these and other objects in view which will be hereinafter fully described and particularly pointed out in the claims, the invention consists in the novel construction and arrangement of parts illustrated in the accompanying drawings forming a part of this specification, in which:—

Figure 1 is a front elevation of a signal embodying my invention,

Fig. 2 is a sectional view in front elevation,

Fig. 3 is a sectional view in side elevation,

Fig. 4 is a horizontal section on the line 4—4 of Fig. 1,

Fig. 5 is a vertical section of the switch operating mechanism,

Fig. 6 is a top plan view of the same,

Fig. 7 is a horizontal section on the line 7—7 of Fig. 5,

Fig. 8 is a diagrammatical view showing the wiring plan of the device.

Like characters of reference indicate like parts in the various views.

In the drawings 1 designates a casing having the top, bottom, end sides, and front formed in one piece, and having the rear 2 thereof secured to the adjacent ends of the top and end sides by means of screws 3. A bracket 4 is mounted within the casing and is spaced from the front thereof, and a hollow shaft 5 is mounted for rotation in bearings formed in the front of the casing and the bracket 4. The front end of the shaft 5 extends exteriorly of the casing, and a cylindrical casing 6, disposed at right angles to the shaft 5, is mounted upon said shaft by

means of a laterally extending boss 7 formed near the upper end thereof. An end 8 is screw threaded into the lower end of the casing 6, and an electric light socket 9, of usual construction, is mounted upon the upper surface of said end within the casing, and an electric light globe 10 is mounted in said socket and extends upwardly therefrom. An end 11 is screw threaded into the upper end of the casing 6 and has a centrally disposed aperture 12 formed therein, which lies directly above the globe 10. A frame 13 is looped above the aperture 12 and has ears formed at the ends thereof, which are secured upon the upper surface of the end 11 on either side of the aperture 12 by means of screws 14. The frame 13 is disposed in line with the axis of the casing 6, and the loop formed thereby is elongated and flares at the upper end thereof. A continuous longitudinal groove 15 is formed in the loop forming portion of the frame 13 and is disposed upon the opposing surfaces thereof, and the edges of a pair of oppositely disposed concave transparent members 16 are engaged by the groove 15 and form an inclosure, the lower portions of the members 16 being spaced apart at the center portions thereof and communicating with the aperture 12 whereby the light of the globe 10 enters the inclosure formed by the transparent members 16. The transparent members 16 may be colored, preferably red, and an arrow 17 is inscribed thereon in line with the axis of the casing 6, as indicated. The hollow shaft 5 extends through the casing 6 into the inclosure thereof and electric conductors 18 connected to respective terminals of the socket 9 are led through said shaft into the casing 1.

A disk 19 is fixedly mounted upon the hollow shaft 5, and a gear 20 is rotatably mounted on said shaft and adapted to engage the surface of said disk with its web. A spring disk 21 is disposed upon said shaft and engages the opposite surface of the web of said gear with the outer edge thereof, said spring disk being dished rearwardly from the edges thereof, and a collar 22 is secured upon said shaft by means of a set screw 23 and is disposed at the rear of the spring disk 21 whereby the gear 20 may be held in frictional engagement with the disk 19. An electric motor 24 of usual construction is mounted within the casing 1 and has the shaft 25 thereof extending at right angles to the shaft 5 and disposed below the same. The outer end of

the shaft 25 is journaled in a bracket 26, and a worm 27 is formed upon said shaft and meshes with the teeth of the gear 20.

- In the preferred embodiment of my invention I have provided three signaling positions therefor, the (straight ahead) position being indicated in full lines in Fig. 1, and the (left) and (right turn) positions being indicated in dotted lines in the same figure.
- 5 I have provided means for locking the signal in its various signaling positions which will now be described. Fixedly mounted upon the shaft 5 in front of the disk 19 is a locking disk 28 which has three slots 29 formed 10 in the periphery thereof to correspond with each signaling position, as above noted. Secured upon the top of the casing 1 is a bracket 30, which extends downwardly and has a latch member 31 mounted therein 15 adapted to engage any one of the slots 29, incident to the position of the signal. A spring 32 is mounted upon the bracket 30 and engages the latch member 31 to normally retain the same in engagement with the locking disk 28. An electromagnet 33 is mounted 20 upon the adjacent end wall of the casing and the core thereof is disposed in alignment with the latch member 31. An armature 34 is mounted upon the latch member 31 and is 25 disposed adjacent to the core of the electromagnet 33, the disposition of the parts being such that when the electromagnet 33 is energized it withdraws the latch member 31 from engagement with the locking disk 28 against 30 the influence of the spring 32.
- A bracket 35 is secured upon the bottom of the casing 1 and extends downwardly therefrom and terminates in a circular disk member 36 having one side thereof serrated. 35 Another bracket 37 has a correspondingly serrated disk member 38 formed thereon and adapted to engage the disk member 36, said disk members being secured together by means of a centrally disposed screw 39 threaded into the member 36 and engaging 40 the disk member 38 with the headed end thereof. The bracket 37 may be secured upon a motor car, and the signal adjusted by means of the screw 39 and the engaged 45 disks to assume a vertical position.
- The actuators of the motor 34 and the electromagnet 33 are controlled as follows: Located in proximity to the operator of the vehicle is a controlling switch 40 which comprises generally a casing 41 having a removable cover 42, which is located at the side of the casing, and a handle 43 adapted to swinging movement and lying above the top of the casing. A vertical shaft 44 has 50 its lower end journaled in the bottom of the casing, a flange 45 formed on said shaft engaging the upper surface of the bottom of the casing to prevent downward longitudinal movement of this shaft. A second vertical shaft 46 has its upper end jour-

naled in the top of the casing and is disposed in axial alignment with the shaft 44. A disk 47 is mounted upon the shaft 44 near the upper end thereof, and that portion of the shaft which lies above the disk 47 is journaled in a bearing formed in the lower end of the shaft 46. The outer surface of the lower end of the shaft 46 is angular in cross section, as designated at 48, and a disk 49 is mounted upon said angular portion for 75 longitudinal sliding movement. A coil compression spring 50 encircles the shaft 46 above the disk 49, and a flange 51 is fixedly mounted upon the shaft 46 above said spring, the spring being of sufficient length to engage the flange 51 and the disk 49 with its respective ends to hold the disk 49 in frictional engagement with the disk 47. A switch arm 52 is mounted upon the shaft 46 and engages the lower surface of the top of 80 the casing with the upper surface of its hub to prevent upward lateral movement of the shaft 46. The handle 43 is mounted upon the shaft 46 above the top of the casing by means of a tapered pin 53. The switch arm 52 extends laterally from the shaft 46, and the outer end thereof is adapted to engage one of three contacts 54, 55 and 56 in the various positions thereof. Each of these contacts is mounted upon the side 85 wall of the casing by means of bolts 57, and insulated from the walls of the casing by insulating blocks 58. The movement of the handle 43 is limited by means of two stops 59 formed upon the top of the casing and so 90 disposed that when the handle is in engagement with one of the stops the switch arm 52 engages the contact 54, and when the handle engages the other stop the switch arm 52 engages the contact 56, the contact 55 being 95 engaged by the switch arm 52 when the handle 43 is at a point intermediate the stops 69. In order that the operator may easily determine when the switch arm 52 is engaged with the contact 55, a flat spring 60 is mounted 100 upon the handle 43 and has a downwardly extending button formed upon the free end thereof which is adapted to engage a depression 62 in the top of the casing when said switch arm is engaged with the 105 contact 55.

A cylindrical insulating member 63 encircles the shaft 44 and is disposed between the disk 47 and the flange 45 and is secured upon said shaft by means of a tapered pin 110 64. A pair of switch arms 65 are fixedly mounted upon the insulated member 63 and extend laterally therefrom and are adapted to engage contacts 66, 67 and 68, the arms being so disposed relative to each other that 115 when one arm is in engagement with the contact 66 the other arm is in engagement with the contact 67, and when the first mentioned arm is in engagement with the contact 67 the second mentioned arm is in engagement with the contact 68. A second cylindrical insulating member 69 encircles the shaft 46 and is disposed between the flange 51 and the flange 45 and is secured upon said shaft by means of a tapered pin 120 70. A pair of switch arms 71 are fixedly mounted upon the insulated member 69 and extend laterally therefrom and are adapted to engage contacts 72, 73 and 74, the arms being so disposed relative to each other that 125 when one arm is in engagement with the contact 72 the other arm is in engagement with the contact 73, and when the first mentioned arm is in engagement with the contact 73 the second mentioned arm is in engagement with the contact 74.

gagement with the contact 68. The contacts 66, 67 and 68 are secured within the casing upon an insulating member 69 which is secured to the wall of the casing by means of 5 headed screws 70. The contacts 66 and 68 have upwardly extending stops 71 adapted to engage the respective switch arm 65 when the same is in engagement with respective contacts 66 and 68. By means of the stops 10 71 the rotation of the shaft 44 is limited, and when the direction of movement of the shaft 46 is reversed the initial reverse movement thereof is transmitted to the shaft 44, through the frictional engagement of the 15 disks 47 and 49, and the switch arms 65 are moved to the opposite extremity of their paths of movement where the respective switch arm engages the respective stop 71 and the movement of the switch arm is 20 stopped. It will be noted at this point that the amount of movement required of the shaft 44 to move the switch arms 65 from engagement with one pair of contacts into engagement with another pair of contacts is 25 less than the movement which is required of the switch arm 52 in moving the same from one of the contacts 54, 55 and 56 to another of said contacts, and after the initial reverse movement of the shaft 46 has moved the 30 switch arms 65 to their disposed positions the disk 49 slips upon the disk 47 so that the shaft 46 may be rotated further to properly engage the switch arm 52 with the selected contact thereof.

35 Mounted upon the inner end of the shaft 5 are two commutators 72 and 73, which are engaged by respective spring contact blades 74 and 75 which are mounted upon the top of the casing 1. Both of the commutators 40 are semi-circular, and the commutator 72 has an insulated portion 76 located at the middle portion of the commutator, and the commutator 73 has two insulated portions 77 and 78 disposed at either end of the same. The 45 conductive portions of the commutator 72 are in electrical communication with each other. The commutators 72 and 73 are so timed relative to the signal that when the signal is in its (straight ahead) or vertical position, as designated in Fig. 1, the contact 50 74 engages the insulated portion 76 thereby opening the circuit through the commutator 72, the contact 75 engaging the conductive portion of the commutator 73 and closing the circuit through said commutator. When 55 the signal is in either one of its (right) or (left turn) positions, as indicated in dotted lines in Fig. 1, the contact 75 engages either one of the insulated portions 77 or 78, as 60 the case may be, and the contact 74 engages the conductive portion of the commutator 72 whereby the circuit through the commutator 73 is open and the circuit through the commutator 72 is closed.

65 Referring to Fig. 8, 79 indicates the field magnets of the motor, the same being of usual construction and requiring no further description for the present purposes. The opposite terminals of the field magnets 79 are connected with respective switch arms 70 65 by conductors 81 and 82 respectively. The contacts 66 and 68 are connected to one brush of the motor by a branching conductor 83, and the opposite brush of the motor is connected to the contact 67 by a conductor 75 84. By the above engagement, it will be noted that by moving the switch arms 65 to their different positions to engage different pairs of the contacts 66, 67 and 68 the poles of the field magnets 79 may be reversed 80 relative to the commutator 80, and the motor may be reversed thereby. 85 designates a suitable source of electric energy, and a conductor 86 leads from one pole thereof to one brush of the commutator 80. A conductor 85 87 leads from the opposite pole of the source of energy 85 and communicates with the switch arm 52. It will be noted at this point that the contact 55 is disposed between the contacts 54 and 56, and the switch arm 90 52 in passing from one of the contacts 54 or 56 to the other will pass over the contact 55. A conductor 88 leads from the contact 55 to the contact 74 to the commutator 72, and a branching conductor 89 leads from contacts 95 54 and 56 to the contact 75 of the commutator 73. A branching conductor 90 leads from the commutators 72 and 73 to the brush of the commutator 80 which lies opposite the brush to which the conductor 86 100 is connected. The opposite terminals of the electromagnet 33 are connected to respective brushes of the commutator 80 by conductors 91 and 92 respectively.

The position of the switch arms 52 and 65 105 in Fig. 8 are positioned to correspond with the vertical or (straight ahead) position of the signal as shown in Fig. 1. When it is desired to move the signal from this position to indicate a left turn the switch arm 110 55 is moved by means of the handle 43 to engage the contact 54. This closes the main circuit to the signal through the commutator 73 whereupon the motor starts rotating, and the electromagnet 33 is energized 115 to withdraw the latch member 31 from engagement with the respective slot 29. As soon as the latch member 31 is withdrawn the signal is turned by the motor through the frictional engagement of the gear 20 120 with the disk 19. When the signal reaches its (left turn) position the insulated portion 77 of the commutator 73 engages the contact 75 and the circuit is opened, the electromagnet 33 being deenergized thereby and allowing the latch member 31 to engage the proper slot 29, and the motor 24 discontinues its rotation. When it is desired to move the signal back to (straight ahead) position or to (right turn) position the switch arm 52 125 130

is moved back as before described to engage either the contact 55 or the contact 56. Upon the initial reverse or backward movement of the switch arm 52 the frictional driving connection between the shaft 46 and the shaft 44 rotates the switch arms 65 to the right until the respective switch arm engages the respective stops 71 of the contact 68. This reverses the poles of the fields 79 and 10 the motor is ready to turn in a reverse direction, and it will be noted at this point that the pole changing switch is operated to reverse the fields of the motor by the switch arm 52 which engages the contact 55. As 15 the switch arm 52 engages the contact 55 the main circuit is completed through the commutator 72, the insulated portion 76 thereof being out of engagement with the contact 74. When the circuit is completed as above 20 described the electromagnet 33 withdraws the latch member 31 and the motor 24 rotates in the opposite direction to bring the signal to (straight ahead) position. If it is desired to maintain the signal in (straight 25 ahead) position the switch arm 52 is moved in engagement with the contact 55 and the main circuit is opened as the insulated portion of the commutator 72 engages the contact 74. If it is desired to move the signal 30 to (right turn) position the movement of the switch arm 52 is continued until it engages the contact 56, and when the signal assumes the (right turn) position the insulated portion 78 of the commutator 73 will engage 35 the contact 75 and the circuit through the commutator will be opened. It will be noted that in moving the signal from either left turn position to right turn position or from right turn position to left turn position, it 40 is necessary to have the switch arm 52 momentarily engage the contact 55 to move the signal so that the contact 75 of the commutator 73 engages a conductive portion of the commutator, whereupon the switch arm 52 45 may be moved to the desired contact 54 and 56 and complete the main circuit through said commutator 73. In the operation of the device the mere passing of the switch arm 52 over the contact 55 will accomplish 50 this and it requires no attention on the part of the operator.

Having thus fully described my invention, I claim:-

1. In a device of the character described, 55 the combination with a movably mounted signal, electroresponsive means having operable connection therewith and adapted to move the same in either direction, a pole changing switch connected with said electro- 60 responsive means and adapted to control the direction of the movement of the same, a main circuit including said electroresponsive means, commutators connected with said main circuit and having gaps therein adapt- 65 ed to open said main circuit, the gaps of each

of the said commutators being spaced to open the circuit therethrough when the circuit through another of said commutators is closed, and a multi-point switch in said main circuit adapted to close the same through 70 another one of said commutators.

2. In a device of the character described, the combination with a movably mounted signal, electroresponsive means having connection therewith and adapted to move the 75 same in either direction, a pole changing switch connected with said electroresponsive means and adapted to control the direction of the movements of the same, a main circuit including said electroresponsive means, 80 commutators connected in parallel in said main circuit and having gaps therein adapted to open said main circuit, the gaps of each of the said commutators being spaced to open the circuit therethrough when the circuit 85 through another of said commutators is closed, and electroresponsive means in operable relation with said signal and connected in parallel with said first mentioned electroresponsive means, and in series with all of 90 said commutators, and a multi-point switch in said main circuit adapted to close the circuit through any one of said commutators.

3. In a device of the character described, the combination with a movably mounted 95 signal, electroresponsive means having operable connection therewith and adapted to move the same in either direction, a pole changing switch connected with said electroresponsive means and adapted to control the 100 direction of the movement of the same, a main circuit including said electroresponsive means, commutators connected in parallel in said main circuit and having gaps therein 105 adapted to open said main circuit, the gaps of each of the said commutators being spaced to open the circuit therethrough when the circuit through another of said commutators is closed, a multi-point switch in said main circuit adapted to close the same through 110 any one of said commutators, and means having operable connection with said pole changing switch and said multi-point switch, 115 said means being adapted to operate said pole changing switch to reverse the direction of said electroresponsive means to move the signal to the desired position.

4. In a device of the character described, the combination with a movably mounted signal, electroresponsive means having operable connection therewith and adapted to move the same in either direction, a pole changing switch connected with said electroresponsive means and adapted to control the direction of the movement of the same, a main circuit including said electroresponsive means, commutators connected in parallel in said main circuit and having gaps therein 120 adapted to open said main circuit, the gaps of each of the said commutators being spaced 125

- to open the circuit therethrough when the circuit through another of said commutators is closed, a multi-point switch in said main circuit adapted to close the same through any 5 one of said commutators, and means having a fixed driving connection with said multi-point switch for moving the same to its various positions, and a slip driving connection between said means and said pole changing 10 switch whereby said pole changing switch is operated to reverse the direction of said electroresponsive means upon the initial reverse movement of said means.
5. In a device of the character described, 15 the combination with a movably mounted signal, electroresponsive means having operable connection therewith and adapted to move the same in either direction, a pole changing switch connected with said electro- 20 responsive means and adapted to control the direction of the movement of the same, a main circuit including said electroresponsive means, commutators connected in parallel with each other in said main circuit and having gaps therein adapted to open said main 25 circuit, the gaps of each of the said commutators being spaced to open the circuit therethrough when the circuit through another of said commutators is closed and so disposed that the main circuit is open through 30 alternate commutators as the signal is moved from one end of its moves to another, a multi-point switch in said main circuit adapted to close the same through any one of said commutators, and having the contact points thereof arranged to close the circuit through said commutators in the same alternate order as said switch is moved from one end of its operable movement to the other, means having a fixed driving connection 35 with said multi-point switch for moving the same to its various positions, and a slip driving connection between said means and said pole changing switch whereby said pole changing switch is operated to reverse 40 the direction of said electroresponsive means upon the initial reverse movement of said means.
- In testimony whereof I affix my signature.
EDWIN L. STORER.
